HOLDER FOR MINERS' LAMP

James Leo Hostetler, Leavenworth, Kans.

Application September 25, 1943, Serial No. 503,819

2 Claims. (Cl. 240—60)

This invention relates to holders for miners' lamps, such as are commonly used for holding carbide and similar lamps securely in place upon the cap of a miner, and the main object of the invention is to provide a relatively simple and efficient form of holder for this purpose, that can be constructed of very few parts and at low cost.

Another object of the invention is to provide a miners' lamp holder that may be readily attached to conventional forms of caps worn by miners, the device being constructed substantially of a single length of wire of suitable gauge for the purpose and bent upon itself to form and provide the several required elements necessary in such a lamp holder.

Another object of the invention is to provide a miners' lamp holder the main portion whereof is constructed of a single length of heavy wire bent upon itself to form and provide the several necessary elements of such a holder, and including a pair of spaced fingers arranged for attachment to the visor or "bill" of a miners' cap, a pair of spaced and horizontally aligned arcuate arms for resiliently engaging the body of the lamp, a pair of spaced stems for passing vertically up the front of the cap, a pair of spaced fingers for positioning horizontally over the crown of the cap, including means of attachment to the crown and a centrally positioned loop projected over the frontal margin or edge of the crown for engaging the hook of the lamp.

With the foregoing objects in view, together with such other and additional objects and advantages as may appear from the specification, attention is directed to the accompanying drawings wherein is embodied certain preferred forms of the invention and structural features thereof, and wherein:

Figure 1 is a perspective view showing a form of the invention as mounted upon a miners' cap of a conventional type formed with a cylindrical crown portion and with a visor projected forwardly at the lower frontal margin thereof.

Figure 2 is a top plan view of the form of the invention as shown in Figure 1, the holder being shown on an enlarged scale.

Figure 3 is a side elevation of the invention as shown in Figure 2.

Figure 4 is a frontal elevation of the holder as shown in Figure 2.

Figure 5 is a perspective view showing a form of the invention designed for mounting upon another conventional type of miners' cap, commonly styled the "helmet" type of cap, the holder

being here shown as provided with an adjustable extension link, for supporting the device from the center of the crown of the cap, rather than from the frontal portion thereof.

5 Figure 6 is a top plan view of the holder as shown in Figure 5.

Figure 7 is a detail on an enlarged scale of the slide connector or connecting sleeve, for adjustably connecting the extension link to the main portion of the lamp holder.

10 This invention is a lamp holder or bracket designed for attachment to any conventional form of miners' lamp, and the adaptations as shown in the drawings, to two forms of such caps, will 15 illustrate its adaptability to any conventional form of miners' cap, with very slight if any modification.

15 As shown in Figures 1 to 4, the invention is 20 designed for attachment to a box-like form of miners' cap 5, formed with a cylindrical or box-like crown 6, and having the forwardly projected visor or "bill" 7 extended at the lower frontal margin.

25 The lamp holder 8 of this form of the invention is formed almost wholly of a single length of wire of suitable gauge, this length of wire being 30 bent upon itself to form a pair of lower and laterally spaced visor attachment fingers 9, these fingers being formed at the ends of the length 35 of wire, and the extremities of these ends being looped back to provide eyelets 10 adapted to receive rivets 11, whereby the holder is secured 40 frontally upon the cap, by passing the rivets through the eyelets and through the visor 7 of the cap. At a suitably spaced point inwardly 45 of the eyelets 10, the wire at each side is turned vertically upward as at 12 to provide the lower laterally spaced stems 13. Thence the wire at each side is turned outwardly as at 14 to a suitable 50 distance, as to the point 15, where the wire at each side is bent sharply back upon itself and returned to the point 14, thus providing the resilient clamping arms 16, laterally spaced in horizontal alignment and curved outwardly as shown,

45 and thus adapted to receive and hold the body of the conventional miners' lamp as indicated at 55 17 in dotted lines. From the point 14 at each side the wire is then extended upward a suitable space to provide the upper stems 18 which correspond in length to the height of the crown of the cap 5, or to the point 19 at each side. At this latter point the wire at each side is turned 60 inwardly across the crown of the cap, or to the point 20 at each side where the wire is bent sharply back upon itself to form the eyelets 21

and to complete the attachment fingers 22. The connecting bight 23 of the length of wire now spans the bases of the fingers 22, and it is looped outward at its medial point to form the open link 24 for engaging the lamp hook 17a of the lamp 17. The fingers 22 are secured to the crown of the cap by means of the rivets 25 passed through the eyelets 21 and through the crown of the cap. Of course, the construction of the device from the length of wire might begin at the medial portion thereof instead of at the ends, and the link 24 might be first formed, and then the fingers 22, stems 18, arms 16, stems 13 and fingers 9, in reverse order to the procedure as first outlined.

In the use of this form of the holder the lamp 17 is inserted within the resilient arms 16, which readily spread for the purpose, and the hook 17a is inserted through the link 24, thus supporting the lamp securely in place, with the bottom thereof resting upon the lower attachment fingers 9. If found necessary or desirable, a reinforcing cross link 26 may be looped at its ends as shown at 27, around the lower portions of the upper stems 18, to prevent these stems from spreading apart laterally too much, under the load of an inserted lamp.

A modification of the invention is shown in Figures 5 to 7, the same being adapted for use upon another conventional type of miners' cap, ordinarily referred to as the "helmet" type of cap. In this type of cap the crown 6a is usually of rather flexible material, and there is a pair of open links 27a, 28, extended in overlapped relation rearwardly across the crown, the forward link 27a having its forward ends pivotally coiled around the connecting bight 23a overlapping the crown from the points 19a at each side. This coiled and pivotal form of connection of the ends is indicated at 29. In this form the attachment fingers 22 of the previously described form are omitted. An open connecting sleeve 30 embraces the overlapping links 27a, 28, and by the means of a short bolt 31 passed through the closed side of this sleeve and through the links 27a, 28, and into threaded engagement with a relatively wide nut 31a positioned at the under side of the links, the elements may be readily and releasably locked to any adjusted degree of extension as may be found desirable. A rivet 32 is passed through the rear end of the rear link 28 and through the crown of the cap, and serves to secure the elements in place upon the cap. In other respects the structural features of this form of the inven-

tion are similar to those of the previously described form. The rivet 32 is ordinarily seated through the center of the helmet type of cap. By this arrangement a certain degree of adjustability is provided for the elements of the assembly, and the links 27a, 28 may be readily bent to conform to the shape and form of any conventional miners' cap.

It is thought that the construction, operation and use of both forms of the lamp holder will be readily understood from the foregoing description, and the structural features as herein set out and shown, may be varied within the scope of the claims.

15 I claim:

1. In a miners' lamp holder for mounting upon a miners' cap having a frontal visor at its lower margin, the said lamp holder being constructed of a single length of wire and including a pair of double-stranded and laterally spaced crown attachment fingers formed medially of the length of wire and adapted for positioning horizontally over the crown of the cap in transversely aligned spaced relation, the rear ends of these attachment fingers being formed as eyelets for securing the device to the crown, a forwardly disposed single-stranded connecting bight for the said fingers, an open link extended forwardly and centrally from the connecting bight of the crown attachment fingers and adapted for engaging the lamp hook of the miners' lamp, single strands of wire extended vertically down the front of the cap in laterally spaced relation to transversely aligned medial points of the cap, a pair of double-stranded and arcuate lamp clamping arms extended horizontally forward from the cap in laterally spaced relation, single wire strands extended vertically downward at the front of the cap to the cap visor in longitudinal alignment with the said upper vertical stands, and a pair of lower and laterally spaced visor attachment fingers extended outward over said visor, the extremities of said attachment fingers being looped back to form attachment eyelets for securing the device to the visor of the cap.

2. In a device according to claim 1, means for securing the eyelets of the crown attachment fingers and the eyelets of the visor attachment fingers to the crown and visor respectively, and means for reinforcing and bracing the said vertically extended strands of wire at the front of the cap.

JAMES LEO HOSTETLER.
